CAN FILLING APPARATUS

Filed July 5, 1923

2 Sheets-Sheet 2

UNITED STATES PATENT OFFICE.

STEWART E. LAUER, OF ST. LOUIS, MISSOURI, ASSIGNOR TO YORK PRODUCTS CORPORATION, OF CHICAGO, ILLINOIS, A CORPORATION OF ILLINOIS.

CAN-FILLING APPARATUS.

Application filed July 5, 1923. Serial No. 649,503.

To all whom it may concern:

Be it known that I, STEWART E. LAUER, a citizen of the United States of America, residing at the city of St. Louis, in the State of Missouri, have invented certain new and useful Improvements in Can-Filling Apparatus, of which the following is a specification, reference being had therein to the accompanying drawing.

10 My invention relates to filling apparatus and has for its object to simultaneously charge each of a plurality of containers, such as ice-machine water cans, with a predetermined and equal quantity of liquid.

15 While primarily designed for use in connection with ice-plant equipment, the invention is capable of use wherever a number of liquid-containers is desired to be rapidly filled with a uniform quantity of contents.

20 Other features incidental to my invention will be disclosed in the following description.

Drawings.

25 Fig. 1 is a top plan view of an apparatus embodying my invention, with the cans to be filled shown in place.

Fig. 2 is a longitudinal vertical sectional view of the same taken on the line 2—2 of Fig. 1.

30 Fig. 3 is a transverse sectional view of the same taken on the line 3—3 of Fig. 1.

Fig. 4 is a perspective view of the inlet and discharge valve mechanism employed in my invention, the outlet valve-shaft being 35 partially broken away.

Fig. 5 is an enlarged vertical midsectional view of one of the outlet valves.

Description.

40 The cans or other containers 6 are set in alinement in front of the apparatus, as shown in Figs. 1 and 3, and are then in position to receive their contents from the discharge spouts 7, which extend downwardly and outwardly from the bottom 8 of the measuring-tank housing 9 as shown in Figs. 2 and 3.

45 The housing 9 is divided by the walls 10 into a series of uniform compartments 11 fed by nozzles 12, and a single float-valve compartment 13, of the same dimensions and capacity as the compartments 11, but filled by overflow from the adjacent compartments 11 which adjoins it on both sides.

50 55 The tank-housing 9 is mounted on columns

14 at a suitable height to permit the nozzles 7 to discharge their contents at a point above the plane of the containers 6.

The pipe 15 communicates with the valve 16 of usual construction, and which valve 16 is closed when the valve-rod 17 is in raised position.

The feed-pipe 18 extends from the valve 16 through the several compartments 11 and the float-valve compartments 13 and has a 65 nozzle 12 in each of the compartments 11, as shown in Figs. 1 and 2.

The walls 10 are each provided at their tops with a vertically-adjustable flange 19 (see Figs. 2 and 3) whose adjustment is 70 accomplished by means of the winged-nut belt, 20.

On top of the valve 16 I provide a yoked standard 21 in which is fulcrumed the bar 22, pivotally secured to the fork 23 which 75 forms the upper terminal of the valve-rod 17.

At its free end the bar 22 has the block 24 in which the pin 25 (carrying the globular float 26) is adjustably secured by means 80 of the set-screw 27.

The forked guide 28 seated atop the valve 16 as shown in Fig. 4 serves to keep the bar 22 in proper alinement with the valve-rod 17.

85 Through the tank-housing bottom 8 and connecting with and forming the entrances to the spouts 7 are the valve-seat tubes 29 illustrated in section in Figs. 3 and 5, having a central bearing-block 30 whose bore 31 receives and forms a guide for the valve-pin 32; the upper terminal of said pin 32 having the block 33 provided with the eye 34 to be secured to the wire 38 (see Fig. 4). On the pin 32 are secured the conoidal metallic top 35 and resilient bulbous depending face 36 forming together the valve A, the face 36 registering with the inwardly-beveled upper mouth 37 of the tube 29, as shown in enlarged detail in Fig. 5. The bore 31 is sufficiently large to afford considerable clearance for the valve-pin 32, so that the valve A will be accurately seated even if the apparatus should become slightly displaced from a true vertical position.

100 105 110 The outlet-valve-shaft 39 is journaled in bearings 40—40 and has at one end the hand-lever 41, secured to it by the clamp 42, the free end of said hand-lever 41 extending through the guide-plate 43 having the slot

44 with terminal lever-holding notches 45 and 46. The valve-supporting wires 38 are secured to the valve-shaft 39 by means of arms 47 detachably and adjustably mounted on the valve-shaft 39 by means of clamps 48. The trip-arm 49 is similarly mounted on the valve-shaft 39 by means of the clamp 50.

Mode of operation.

10 The co-operation of the inlet and outlet valves is shown in Fig. 4, which illustrates the valve 16 in open position, admitting liquid to the compartments 11 and 13 (13 being 15 filled by overflow from the adjoining compartments 11 as above described); the valve A being in closed position, seated in the upper mouth of the tube 29. The trip-arm 49 is rigidly held in the illustrated position by 20 the engagement of the hand-lever 41 with the notch 45. The liquid in the compartment 13 will finally rise to a height which will carry the float 26 upward to elevate the valve-rod 17 and close the valve 16 shutting off the flow through the inlet-pipe 18. The 25 compartments 11 and 13 at this stage will contain an equal amount of liquid, which will be released and discharged by 30 disengaging the hand-lever 41 from the notch 45, moving it rearwardly through the slot 44 and locking it in the notch 46, there to remain, locking the valve 16 closed until 35 the contents of the compartments 11 and 13 have been completely discharged.

35 The over-flow pipe 51 is arranged to take care of accidental excess of liquid in the compartments 11 and 13.

It should be noted that the nozzles 12 are 40 so stationed as to be above the level of the liquid when the compartments 11 and 13 are filled, to prevent the occurrence of possible siphoning action.

45 The bulbous depending face 36 of the valve A is preferably of the contour shown in Fig. 5, its outline in section being arcuate at its surface-contact with the mouth 37, and following (in section) the

outline of a circle struck from the center line of the pin 32, thus enabling the face 36 to contact closely with the mouth 37 when seated therein.

The metallic top 35 of the valve A is preferably of sufficient weight to straighten any kinks occurring in the wire 38 and to cause the valve A to be positively seated 55 with firmness.

The working water level is fixed by adjusting the float 26 and the capacity of the compartments 11 is varied at will by raising and lowering the walls 10, thus regulating 60 the weight of the water in each compartment according to the requirements of the refrigerating plant in which the apparatus is employed.

65

Claims.

I claim:—

1. In a can filling apparatus, a housing; a series of vertical walls forming compartments within said housing, each of said walls having a vertically adjustable flange at its top; an inlet pipe; a float-operated valve controlling said inlet pipe; an outlet-valve seated in each of said compartments; a lever controlling said outlet-valves; and locking means interposed between said lever and said float-operated valve to hold said valve in closed position while said outlet-valves are in opened position.

2. In a can filling apparatus, a housing; 80 a series of vertical walls forming compartments within said housing; an inlet pipe having a discharge nozzle in each of said compartments; a float-operated valve controlling said inlet pipe; an outlet-valve seated in each of said compartments; a lever controlling said outlet-valves; and locking means interposed between said lever and said float-operated valve to hold said valve 85 in closed position while said outlet-valves are in opened position.

In testimony whereof I have hereunto affixed my signature.

STEWART E. LAUER.
